Primary Examiner — Patricia Palasik

CLAIM

The ornamental design for a tunable laser assembly, as shown and described.

DESCRIPTION

FIG. 1 is a top perspective view of the tunable laser assembly, FIG. 2 is a right side elevation view thereof; FIG. 3 is a left side elevation view thereof; FIG. 4 is a top elevation view thereof; FIG. 5 is a bottom elevation view thereof; FIG. 6 is a front elevation view thereof; and, FIG. 7 is a rear elevation view thereof.

The broken lines illustrated in the Figures form no part of the claimed design.
